[57] CLAIM

The ornamental design for a solid lubricant block, as shown and described.

DESCRIPTION

FIG. 1 is an isometric view of a solid lubricant block showing a first embodiment of my new design;

FIG. 2 is a right side elevational view of the first embodiment, the left side being a mirror image thereof;

FIG. 3 is a front side elevational view of the first and a second embodiment of the solid lubricant block, the back side being a mirror image thereof;

FIG. 4 is a top plan view of the first and the second embodiment, the bottom of the first embodiment being a mirror image thereof;

FIG. 5 is an isometric view of the second embodiment;

FIG. 6 is a right side elevational view of the second embodiment, the left side being a mirror image thereof; and,

FIG. 7 is a bottom plan view of the second embodiment.

FIG. 1.

FIG. 4.

FIG. 3.

FIG. 2.

FIG. 5.

FIG. 7.

FIG. 6.
